UNITED STATES PATENT OFFICE.

OLIVER JOHNSTON, OF HUNTINGTON, NEW YORK.

HEATER AND VENTILATOR.

1,133,969.

Specification of Letters Patent.

Patented Mar. 30, 1915.

Application filed November 13, 1914. Serial No. 871,918.

To all whom it may concern:

Be it known that I, OLIVER JOHNSTON, a citizen of the United States, and a resident of Huntington, in the county of Suffolk and State of New York, have invented a new and Improved Heater and Ventilator, of which the following is a full, clear, and exact description.

My invention relates to heaters to be introduced in a stove pipe and arranged to conduct smoke and other products of combustion to the chimney, or to discharge heated air into the room in which the heater is located.

My invention comprises a drum adapted to receive stove pipe connections at the top and bottom. A cold air inlet pipe also leads into the drum at the bottom from a point near the floor of the room. The air inducted through said inlet pipe may be carried off through the top of the drum to the chimney, to effect ventilation of the room. The drum is equipped, however, with means to check the draft to the chimney after the smoke and noxious gases have passed off, and with means whereby the air taken in at the air pipe and heated in the drum, is directed outwardly in a lateral direction into the room, together with more or less of the hot products from the stove or furnace when the smoke and noxious gases have passed off.

The invention will be particularly explained in the specific description following.

Reference is had to the accompanying drawings forming part of this specification, in which similar characters of reference indicate corresponding parts in all the views, and in which:

Figure 1 is a perspective view of a heater and ventilator embodying my invention, portions being broken away; Fig. 2 is a vertical section; Fig. 3 is a horizontal section on the line 3—3 Fig. 2, the upper fan being omitted; Fig. 4 is a perspective view of the bottom of the heater and its appurtenances; and Fig. 5 is a fragmentary detail in vertical section on the line 5—5 of Fig. 1.

In constructing an embodiment of my invention in accordance with the illustrated example, a drum generally designated by the numeral 10 is provided, the drum being preferably cylindrical. The bottom 11 of the drum is provided with a tubular inlet 12 adapted to be connected with a stove pipe section, and the top 13 of the drum is pro-

vided with an outlet 14 adapted to be connected with a stove pipe section, so that the drum may be introduced in a stove pipe between two adjacent pipe sections. Leading into the bottom also is an air inlet pipe 15 which in practice will extend downwardly to a point near the floor of the room in which the heater is located. The side wall of the drum 10 terminates at a considerable distance short of the top 13, the drum being open at the sides at the upper portion. Extending around the drum is a vertically movable shutter 17 slidably fitted on the shell of the drum 10, and having guided movement on the vertical bars 16 by means of keepers 18 on said shutter embracing said bars.

Communicating with the member 12 which connects with the lower stove pipe section is a tubular extension 19 in the interior of the drum. A cross-bar or spider 20 at the top of the extension 19 supports a post 21, and on a collar 22 or like element on said post, is supported a sleeve 23 which forms a rest for a horizontal fan 24 arranged to turn on the post 21 beneath the top 13 of the drum. The fan 24 consists of a series of radially disposed inclined blades secured on a hub 25 which has a cross-bar 26 supported on the sleeve 23.

Above the fan 24 and in fixed relation thereto is a small fan 27 presenting a plurality of spiral blades disposed within the connection 14, which receives the upper stove pipe section. The upper end of the post 21 has a bearing in a cross-bar 28 in the member 14. In the present example the blades of the upper fan 27 are soldered or otherwise fastened as at 29 to certain of the blades of the lower fan 24.

By the described arrangement, the shutter 17 may be maintained in the raised position to effect a complete closure of the drum at the side, until the smoke and other products of combustion have passed through the drum and its outlet 14 to the chimney. At the same time air will be drawn in through the inlet pipe 15 and carried off through the chimney, thereby ventilating the room. Upon the shutter 17 being lowered, however, after the smoke and noxious gases have passed off, more or less of the hot products and the air drawn in through the inlet pipe 15 will pass laterally outward into the room. The draft through the stove pipe

2
and drum, however, will turn the fan 27, and the latter will turn the fan 24 to prevent air from being drawn in through the lateral opening and will cause a portion of the hot products to be forced outwardly through the said lateral opening into the room. The fan 27, in being turned by the products passing therethrough, will more or less check the draft through the drum outlet 14, so that a material portion of the hot products may be available for the heating of the room.

To prevent the possibility of sparks being carried outward through the drum, the open portion of the latter is provided with a screen 30. In order to sustain the annular shutter 17 in the raised position, any suitable fastener may be provided; I have shown for this purpose a catch member 31 formed by an outward bulging of the flange of the cap 13. To engage the catch member 31, the shutter 17 is formed with a depression 17^a and an offset 17^b, the formation resulting in proper engagement with the catch member 31. To raise and lower the shutter 17 I provide a suitable handle 32. I provide means for holding the fan 24 from turning when the shutter 17 is closed. The means employed consists of a stop movable into and out of engagement with the fan. As here shown, the stop is in the form of a pin 33 attached to a chain 34, one end of which is secured to an eye 35 or equivalent on the top 13 of the drum. The pin 33 is adapted to be inserted downwardly through a hole 36 in the top 13 to project between adjacent blades of the fan.

Having thus described my invention, what I claim as new and desire to secure by Letters Patent is:

1. In a heater and ventilator, a drum having an inlet and an outlet at the bottom and top respectively, adapted for connection with stove pipe sections, said drum having a lateral open portion, a movable closure for said open portion, and a fan in the drum at the open portion thereof, arranged to force air and gases from the drum outwardly through said open portion.

2. In a heater and ventilator, a drum having an inlet and an outlet at the bottom and top respectively, adapted for connection with stove pipe sections, said drum being closed at its lower portion and open at the upper portion at the sides, a tubular closure for said open portion, the closure being slideable on the drum, and a fan disposed transversely in the drum at the said open portion,

and having its blades so disposed as to force air and gases from the drum outwardly through said open portion.

3. In a heater and ventilator, a drum having a tubular inlet at the bottom and a tubular outlet at the top, adapted to connect with stove pipe sections, said drum being open laterally adjacent to the top of the drum, movable means for closing the opening, a fan transversely disposed in the drum adjacent to the lateral opening and a second fan disposed in the tubular outlet and in fixed relation to the first fan, said first fan having its blades disposed so as to force air and gases outwardly from the drum laterally through the open portion thereof.

4. In a heater and ventilator, a drum having an inlet and an outlet at the bottom and top respectively, adapted for connection with stove pipe sections, said drum having a lateral open portion, a movable closure for said open portion, an air inlet pipe leading into the drum at the bottom, and a fan in the drum at the open portion thereof, arranged to force air and gases from the drum outwardly through said open portion.

5. A heater and ventilator comprising a drum having an inlet at the bottom and an outlet at the top adapted to connect with stove pipe sections, an air inlet at the bottom of the drum, said drum presenting an annular open portion below the top, bars extending across the open portion and supporting the top, a tubular shutter having guided movement on certain of said bars to cover or uncover said open portion, and a fan in the drum at the open portion, arranged to force air and gases from the drum outwardly through said open portion.

6. In a heater and ventilator, a drum having an inlet and an outlet at the bottom and top respectively, adapted for connection with stove pipe sections, said drum having a laterally open portion, a movable closure for said open portion, an air inlet leading into the drum at the bottom, a fan in the drum at the open portion thereof, and a stop on the drum, the stop being movable into or out of engagement with the said fan to arrest the same or permit rotation thereof.

In testimony whereof I have signed my name to this specification in the presence of two subscribing witnesses.

OLIVER JOHNSTON.
